UNITED STATES PATENT OFFICE.

JOHN K. OLSEN, OF CHICAGO, ILLINOIS, ASSIGNOR TO STEWART-WARNER SPEEDOMETER CORPORATION, OF CHICAGO, ILLINOIS, A CORPORATION OF VIRGINIA.

MAGNETIC SPEEDOMETER.

Application filed August 24, 1925. Serial No. 51,892.

The purpose of this invention is to provide an improved construction in a magnetic speedometer of the split ring type, particularly for economy and simplicity of assembling and dis-assembling the parts and for rendering the temperature compensating devices more reliably effective for their purpose. It consists in the elements and features of construction shown and described, 10 as indicated in the claims.

In the drawings:

Figure 1 is a front elevation of a portion of a combined speedometer and odometer instrument presenting the speedometer parts, 15 the same being removed from the casing of the instrument.

Figure 2 is a section at the line, 2—2, on Figure 1.

Figure 3 is a section at the line, 3—3, on 20 Figure 2.

Figure 4 is a detail section at the line, 4—4, on Figure 3.

The structure shown in the drawings is 25 that of a magnetic speedometer of the split ring type.

The magnet is mounted for rotation by means of a stamping, 10, characterized by its formation in radial section, causing it to comprise a central trans-axial area, 10^a, centrally apertured at 10^b, for attaching it to 30 the shaft by which it is to be rotated as hereinafter described, and, successively encompassing said central area, are annular corrugations, 12 and 13, projecting in opposite directions from the plane of said central area, 10^a, the form of the outer circumferential annular area of the stamping being substantially cylindrical as seen at 15, and diametered to fit the interior diameter of the 35 annular magnet and having the extreme edge flexed outwardly in a transaxial flange, 16, for seating the magnet; and for retaining the latter securely, lugs, 17, 17, 17, are struck out of the sheet metal at the crest of the 40 outermost corrugation, and clinched outwardly around the upper corner of the magnet at the inner circumference thereof opposite the flange, 16, which embraces the opposite corner at said inner circumference as 45 seen in Figure 2. To secure the ring magnet against circumferential displacement with respect to the mount, a lug, 18, is struck from the margin of the mount at which the circumferential flange, 16, is formed, out- 50

wardly into the gap, 20^a, of the magnet, 20, 55 as seen in Figure 2.

B is a thermostatic temperature-change compensator made of a bilaminate metal strip, of which the two laminae are of metals having respectively coefficients of thermal 60 expansion and contraction sufficiently different to cause substantial flexure of the strip to result from changes of temperature likely to be experienced by the instrument in service. This thermostatic compensator has 65 one lamina of iron and the other of copper or copper alloy, and is made from an L-shaped blank of which the shorter limb extends at right angles to the original plane of the blank, and the longer limb is coiled 70 circularly to form a nearly closed ring as seen in Figure 3 with the iron lamina at the outer side of the coil and thereby at the under side of the radially extending limb, B¹. This thermostatic temperature compensator 75 is mounted in the inner upwardly open side of the corrugation, 12, of the magnet mounting stamping, 10, spaced from both sides of the channel of the corrugation free from contact with either wall thereof as seen in 80 Figure 2 with the radial limb, B¹, extending out substantially parallel and slightly removed from contact with the upper surface of the magnet at the magnet gap, 21, over which the said radial limb extends at what 85 may be regarded as the normal position, that is the position which it occupies at ordinary or average atmospheric temperature, say 60° F., said limb, B¹, being spaced from the magnet pole adjacent to which it extends 90 far enough to avoid being flexed into contact with the magnet by the magnetic attraction of the magnet for the iron lamina of the compensator. The mounting and securement 95 of the thermostatic compensator is effected by lugs, b, b, formed projecting from the lower edge of the bi-metallic bar adjacent to the end thereof, the magnet mount, 10, having apertures at 16, 16, in the bottom of the channel of said inner corrugation, positioned 100 to receive said lugs which are clinched over on the opposite side of the stamping.

The ends of the ring magnet facing each other at the gap, 21, are beveled inwardly with respect to the ring as seen in 105 Figure 3 to cause the gap to be tapered widening inwardly; and the radial limb, B¹, of the thermostatic compensator is longitu-

dinally beveled as seen at b^1 to cause the edge which at normal temperature overhangs the gap, to trend at an acute angle to both edges of the gap and to cross the edge 5 past which said limb extends for overhanging the gap, substantially at the point at which the bevel of that edge begins.

It may be understood from the foregoing description that when the temperature of 10 the instrument, including the magnet and the temperature compensator, exceeds that in view of which, as normal, the magnet and compensator are formed and related as described, the magnetic drag on the drag element is diminished, requiring compensation 15 to preserve accuracy of the speed indication; and that the same rise of temperature causing the bilaminar ring of the compensator to contract in radius by reason of the 20 greater expansion of the inner,—copper,—lamina, that of the outer,—iron—lamina, will cause the limb, B^1 , to be retracted circumferentially with respect to the magnet from over the magnet gap which it overhangs, which will diminish the amount of 25 flux conducted across the gap by said limb, and cause a corresponding increase in the flux cut by the drag element, thus offsetting the reduction of electric conductivity and 30 consequent drag susceptibility caused by the rise in temperature. And it will be observed that at the same time that the limb, B^1 , is thus withdrawn circularly, diminishing its overhang over the gap, it is by the 35 same cause flexed laterally and withdrawn laterally from the magnet, thus additionally compensating for the reduction of electric conductivity by the drag element caused by rise of temperature.

40 I claim:—

1. In a magnetic speedometer and the like in combination with a magnet rotor shaft, a metal stamping mount for the magnet having a central area in a plane transverse to 45 the rotor shaft centrally apertured for attachment to said shaft and having annular corrugations concentric with the rotor shaft protruding in opposite directions from the plane of said central transaxial area and terminating as to its outer circumference in a 50 substantially cylindrical flange; a magnet diametered for seating on said cylindrical flange, the latter having its terminal area flanged outwardly, and lugs flexed outwardly 55 from the cylindrical flange at a line parallel to said edge flange, the latter and said lugs gripping the magnet between them.

2. In a magnetic speedometer and the like in combination with the magnet rotor shaft 60 and metal stamping mount for the magnet having a central area in a plane transverse to the rotor shaft and centrally secured to the latter and having annular corrugations concentric with the rotor shaft protruding 65 in opposite directions from the plane of said

central transaxial area; a ring magnet having a gap and mounted on and encompassing said mount; a thermostatic temperature compensator consisting of an integral bilaminar bar coiled with a radius approximating the mean radius of one of said corrugations of the mount and lodged therein and having at one end of the coil a limb extending transversely of the axis of the magnet and comprising a magnetically conducting part overhanging the magnet gap, said compensator being secured rigidly by the other end of the coil to the bottom of the corrugation in the mount, whereby the coil is free to expand and contract radially within the limits of the width of the corrugations and adapted to move as a unit by flexure from its said point of securement throughout its length to and including said gap-overhanging limb, for swinging the gap-overhanging limb more or less over the magnet gap.

3. In the construction defined in claim 2, foregoing, the bilaminar compensator having one of its lamina of iron, said lamina being at the side of the transversely extending limb which is toward the magnet, for constituting the magnetically conducting part thereof.

4. In a magnetic speedometer and the like in combination with the magnet rotor shaft, a metal stamping mount for the magnet having a central area in a plane transverse to the rotor shaft and centrally secured to the latter and corrugated outside said transaxial area; a ring magnet having a gap mounted on and encompassing said mount; a thermostatic temperature compensator consisting of a bilaminar bar having one of its laminae of iron, curved circularly with a radius approximating the mean radius of one of said corrugations of the mount secured at one point of its circular extent rigidly to the mount and free from the point of its said securement to its more remote end, and by said securement positioned normally out of contact with either wall of the corrugation, whereby it is free to expand and contract radially within the limits of the width of the corrugation, said compensator having a limb extending transversely to the rotor shaft and terminating overhanging the magnet gap, the iron laminae of said compensator being at the outer side of the coil and thereby at the side of the limb adjacent to the magnet where the latter overhangs the magnet gap.

5. In the construction defined in claim 2, foregoing the thermostatic compensator being secured in the corrugation of the magnet mount by being formed with lugs projecting from the lower edge near the end to be secured, the mount having apertures in the bottom of the corrugation in which said lugs may be entered and clinched.

6. In a magnetic speedometer and the like, in combination with a magnet rotor shaft, a mount for the magnet and a ring magnet having a gap, mounted on and encompassing said mount; the mount having an annular depression; a thermostatic temperature compensator consisting of a bilaminated bar curved in circular form adapted to occupy said annular depression with clearance there-
10 in upon both sides, having its radius approximating the mean radius of said annular depression, said bar being secured by one end rigidly to the mount, and having projecting from the other end a limb extending outwardly transversely to the rotor shaft and
- terminating partly overhanging the magnet gap from the side of said gap from which the circularly curved part of said bar extends circularly to the point of its secure-
ment to the mount, said bilaminated bar hav-
ing one lamina of iron and the circular part
being curved with said iron lamina at the
outer side, whereby said iron lamina is at the
under side of said limb which overhangs the
magnet gap. 20
25

In testimony whereof, I have hereunto set my hand at Chicago, Illinois, this 12 day of August, 1925.

JOHN K. OLSEN.
